UNITED STATES PATENT OFFICE.

DANIEL G. BUTTS, OF NEW ORLEANS, LOUISIANA, ASSIGNOR TO IVORY GARTER COMPANY, OF NEW ORLEANS, LOUISIANA, A CORPORATION OF LOUISIANA.

GARMENT-SUPPORTER.

1,285,027.

Specification of Letters Patent. Patented Nov. 19, 1918.

Application filed July 28, 1916. Serial No. 111,876.

To all whom it may concern:

Be it known that I, DANIEL G. BUTTS, a citizen of the United States, residing at New Orleans, in the parish of Orleans and 5 State of Louisiana, have invented certain new and useful Improvements in Garment-Supporters; and I do hereby declare the following to be a full, clear, and exact description of the same, reference being had to 10 the accompanying drawings, forming part of this specification.

This invention relates to garment supporters, more particularly to supporters for hosiery, and is especially applicable to hose 15 supporters designed for gentlemen's use. The primary object in view is to provide an exceedingly simple and efficient fastening for connecting the opposite ends of the limb-encircling elastic band, when assembling the 20 latter around the limb of the wearer.

The invention consists in certain novel details of construction and combinations and arrangements of parts, all as will be herein-after described in the preferred form and 25 the novel features thereof pointed out in the claims at the end of the specification.

Referring to the accompanying drawings,—

Figure 1 is a perspective view of a hose 30 supporter provided with the fastening means of the present improvements.

Fig. 2 is an end elevation of the two members of said fastening means assembled in interlocking relation.

Fig. 3 is an enlarged detail view of the 35 hook member of said fastening means.

Fig. 4 is an end elevation of the same.

Like characters of reference in the several figures indicate the same parts.

As shown, the supporter of the present invention embodies a limb encircling member A which is usually made of elastic webbing, one end of which is looped through a ring member B and attached to a slide C, whereby 45 the length of the limb encircling member may be adjusted. Preferably, the ring member B is formed substantially broad and flat for purposes which will hereinafter appear. A loop of fabric is fastened in the ring member B to form two free or independent arms or reaches E and E', which respectively support the two members F, F' of a clasp for engaging the garment to be supported. This clasp for engagement with the garment to be 55 supported may be of any preferred construc-

tion and forms no part of the present invention.

The present invention relates particularly to the fastening means for assembling the limb-encircling member A around the limb 60 of the wearer. At the end of said member A opposite the ring member B is a hook member D. This hook member is preferably constructed in one piece and consists essentially of a plurality of cross pieces d, d', d² 65 connected by the sides D', D² of said member. The end of the webbing is passed between the uppermost cross pieces d, d' and around the bottom cross piece in order to hold the parts together. The hook member 70 D is also formed with an outwardly projecting ring-like portion D³ formed with an outwardly curved offset D⁴. This offset D⁴ is preferably located centrally of the ring-like portion D³ of the member and projecting 75 inwardly from the offset and also slightly upwardly, as shown in Figs. 2 and 4 is a tongue d⁴ adapted to interlock with the ring B. The ring-like portion D³ of the hook member is preferably comparatively 80 thin and broad, as shown, and the flat surfaces afforded on each side of the central offset D⁴ are adapted to have a bearing engagement with the ring B when the two members are assembled into interlocking relation. This relieves the strain on the tongue 85 d⁴ and thereby greatly reduces the danger of said tongue being bent or broken away from the hook member. The tongue itself merely forms a means for retaining the 90 two members of the fastening together laterally, and bears little, if any, of the strain.

The two members B and D of the fastening are preferably formed of sheet celluloid or other non-metallic material, the construction being such that the members may be cut from sheets of this material by means of dies and cutters, without necessitating complicated operations such as are usually necessary in the formation of metal members for 95 the same purpose. If desired, the ring-like portion D³ of the hook member may be bent slightly downwardly from the cross pieces d, d', d² to increase the amount of clearance between the tongue d⁴ and the opposite edge of 100 the webbing wound around the lower cross piece d². This permits easy slipping of said tongue over the ring member B. It will be noted that the broad thin formation of the ring-like portion D³ of the hook member af- 105 110

forwards considerable strength without sacrificing resiliency. The offset D^4 is amply resilient to spring back into place if the hook member is accidentally tread upon, thereby greatly adding to the durability of the device.

What is claimed is:

1. A fastening of the character described, comprising a ring member forming an eye, and a coöperating hook member having a substantially ring-like portion formed with an offset outwardly curving from the plane of the ring-like portion and a tongue inwardly projecting from said offset portion adapted to interlock with said ring member, the surfaces of the ring-like portion of the hook member on each side of the offset and tongue affording bearings for the ring member when the two members are brought into interlocking relation.

2. A fastening of the character described comprising a flat broad ring member forming an eye, and a coöperating hook member having a broad substantially ring-like portion formed with an offset outwardly curving from the plane of the ring-like portion and with flat bearing surfaces on each side of said offset adapted to engage the flat surface of said ring, and a tongue inwardly pro-

jecting from the offset adapted to interlock 30 with said ring member.

3. A clasp member for garment supporters and the like, comprising a plurality of spaced connected bands adapted to be engaged by a loop of a garment supporter, and 35 a broad outwardly projecting, substantially ring-like portion formed with an offset outwardly curving from the plane of the ring-like portion and with a tongue rearwardly projecting from said offset, the surfaces of 40 the ring-like portion on each side of the offset and tongue being adapted to engage a locking ring.

4. A clasp member for garment supporters and the like, formed wholly of non-metallic material, comprising a plurality of spaced connected bands adapted to be engaged by a loop of a garment supporter, and 45 a broad, outwardly projecting substantially ring-like portion formed with an offset outwardly curving from the plane of the ring-like portion and with flat bearing surfaces on each side of said offset adapted to engage a locking ring and a tongue inwardly projecting from said offset, said tongue being positioned intermediate the bearing surfaces.

DANIEL G. BUTTS.
